UNLOADING DEVICE

Karl F. V. Nygaard, Philadelphia, Pa., assignor to
Zelma R. Everett, Philadelphia, Pa.

Application March 7, 1938, Serial No. 194,345

1 Claim. (Cl. 221—107)

My invention relates to a new and useful unloading device and it relates more particularly to an unloading device adapted for the gradual removal of the contents of a vacuum sealed receptacle in gradual predetermined quantities without admitting any substantial amount of air into the receptacle, thus preserving the contents thereof in their freshly packed state free from contamination or deterioration.

10 The construction and operation of my unloading device will be more fully explained in the following specification and the accompanying drawing in which:

Fig. 1 represents a vertical section of the unloading device shown applied to the top of a receptacle such as a bottle.

Fig. 2 represents a plan view of Fig. 1.

Figs. 3 and 4 represent views similar to Fig. 1 showing different steps in the operation of the device.

20 Figs. 5 and 6 represent views similar to Fig. 1 showing modified forms of construction.

Referring to the drawing in which like reference characters indicate like parts, and more particularly to Fig. 1, 8 designates a block having a through opening 10 extending vertically therethrough. The block 8 is also provided with a horizontal bore 12 which intersects the bore 10. In the bore 12 is positioned the revoluble sleeve 14 which is provided with the flange 16 serving as a handle which extends beyond the block 8. The revoluble sleeve 14 is provided with an opening 18 in a wall thereof which opening is adapted to register with the bore 10 as the sleeve 14 is rotated, all as clearly shown in Figs. 1, 3 and 4. The sleeve 14 is provided with the solid end 20 which seats in the recess 22 formed in the adjacent wall of the block 8 and which also abuts against the block 8 in substantially air-tight manner. Within the sleeve 14 is positioned the plunger 24 which is provided with the handle 26 projecting beyond the flange 16. The plunger 24 is adapted to fit within the sleeve 14 in a substantially air-tight manner. The bottom side 45 of the block, as viewed in Fig. 1, is provided with a recess 28 which is adapted to receive snugly the rubber cap 30. Carried by the sleeve 14, and projecting slightly below the lower edge thereof is the cutter 32. 34 designates a bottle or similar receptacle which has been filled with any suitable material under a vacuum and the mouth of which is closed by the cap 36 which may be made of Cellophane, rubber or any other easily 50 cut material.

The operation of the device described is as follows:

Assuming that it is desired to unload the contents of the receptacle 34 without admitting air thereto, I first insert the mouth of the bottle 5 34 into the rubber cap 30 which fits thereover in an air-tight manner. In so doing the cutter 32 pierces the seal 36, and by rotation of the receptacle 34 the seal is entirely cut out. The device is preferably turned up-side-down as 10 shown in Fig. 3 so that the contents of the receptacle 34 may fall by gravity and the handle 16 is turned until the opening 18 in the wall of the sleeve 14 registers with the upper end of the bore 10. The plunger 24 is then withdrawn, as shown 15 in Fig. 3, and some of the contents of the receptacle 34 will fall into the chamber 38 which is formed in the sleeve 14 by the withdrawal of the plunger 24. In this position the solid wall of the sleeve 14 closes the other end of the bore 20 10 as best seen in Fig. 3. With the plunger 24 still in its outer position the handle 16 is again turned to bring the solid wall of the sleeve 14 into registration with the end of the bore 10 to which the mouth of the receptacle 34 is applied 25 and this also brings the opening 18 in the sleeve 14 into registration with the lower end of the bore 10. This establishes communication between the chamber 38 and the outside so that the contents of the chamber 38 are now permitted 30 to drop into any desired receptacle such as a cup, spoon, or the like, all as best seen in Fig. 4. If desired the plunger 24 can be provided with markings 40 which indicate the size of the chamber 38 formed by the withdrawal of the plunger 35 and which therefore predetermine the amount of material being withdrawn by each stroke of the plunger. Also, I may use suitable markings 44 and 42, placed on the revoluble sleeve 14 and the block 8 respectively to indicate the relative 40 positions of the sleeve 14 and the block 8 respectively, and the consequent registration or lack of registration of the opening 18 at either end of the bore 10. In lieu of the markings 42 and 44 I may use internal stops so that, when the handle 16 is turned in one direction as far as it will go, the opening 18 of the sleeve 14 will register with one end of the bore 10 and with the mouth of the receptacle 34 as shown in Fig. 3, and, when the handle 16 is turned in the opposite direction as far as it will go, the opening 18 registers with the other end of the bore 10 and the solid wall of the sleeve 14 registers with the end of the bore 10 to which the mouth of the receptacle 34 is applied as shown in Fig. 4. It 55

will thus be seen that the opposite ends of the bore 10 are alternately opened and closed so that when the end of the bore 10 registering with the opening 18 is open to permit discharge of the contents thereof, the other end of the bore 10 is closed to prevent the entry of air into the chamber 38. After the contents of the chamber 38 have been discharged in the position illustrated in Fig. 4, the plunger 24 is again returned to the position shown in Fig. 1 in which it drives out any air that may have entered the chamber 38 while the contents thereof were being discharged.

In Fig. 5 I have shown a slightly modified form of construction in which I remove a portion of the end wall of the block 8 and replace it by the plug 46 which is threaded to the rest of the block 8 at 48. Through the plug 46 I extend the screw bolt 50 which is provided with the wing nut or the like 52. The end wall 54 of the sleeve 14 is secured by the screw 56 to the plate 57 which sits in a recess in the plug 46, and between the plug 46 and the wall 54 is positioned the head 58 of the screw bolt 50. In this construction the sleeve 14 is tapered with its largest diameter being near the handle or flange 16, and by turning the wing nut 52 I may draw the tapered sleeve 14 tightly within the correspondingly tapered, horizontal bore 12 of the block 8 thus effecting a tighter engagement.

In Fig. 6 I have shown substantially the same construction as that shown in Fig. 5 except that the plate 57 which receives the screws 56 also serves as the head of the bolt 50. In this construction I have shown the device as applied to the mouth of an inverted can 60. The operation of the modified forms shown in Figs. 5 and 6 is identically the same as that described in connection with Figs. 1 to 4.

Having thus described my invention, what I claim as new and desire to secure by Letters Patent is:

In an unloading device of the character stated, a body portion having a through-bore therein, one end of said bore serving as an inlet and the other end of said bore serving as an outlet, an annular resilient seal at the inlet end of said bore for engaging in air-tight manner the discharge end of a hermetically sealed receptacle the content of which is to be unloaded, a cutter carried by said body portion in proximity to said inlet end and projecting into said seal for breaking the seal at the discharge end of said receptacle, a sleeve rotatably mounted within said casing, there being an opening in a wall of said sleeve adapted to register with the inlet or outlet in said body portion at will, and a slidably mounted plunger snugly fitting within and normally completely filling said sleeve.

KARL F. V. NYGAARD.
